UNITED STATES PATENT OFFICE

141,097

DESIGN FOR A VENDING CABINET OR SIMILAR ARTICLE

Samuel Pinanski, Brookline, Mass., assignor to Stanway Vending Machines, Inc., Boston,
Mass., a corporation of Massachusetts

Application February 1, 1945, Serial No. 117,712

Term of patent 14 years

(Cl. D52—2)

To all whom it may concern:

Be it known that I, Samuel Pinanski, a citizen of the United States of America, residing in Brookline, in the county of Norfolk and Commonwealth of Massachusetts, have invented a new, original, and ornamental Design for a Vending Cabinet or Similar Article, of which the following is a specification, reference being had to the accompanying drawing, forming a part thereof.

Fig. 1 is a front perspective view of a vending cabinet showing my new design;

Fig. 2 is a rear elevational view thereof on a smaller scale.

I claim:

The ornamental design for a vending cabinet or similar article, substantially as shown.

SAMUEL PINANSKI.
